Primary Examiner — Leanne Was-Englehart(74) *Attorney, Agent, or Firm* — Gerald E. Helget; Taft Stettinius & Hollister LLP(57) **CLAIM**

The ornamental design for a stud for buildings, as shown and described.

DESCRIPTION

FIG. 1 is a front perspective view of a stud for buildings, showing my new design;
 FIG. 2 is a right side elevational view of a stud for buildings;
 FIG. 3 is a front elevational view of a stud for buildings;
 FIG. 4 is a left side elevational view of a stud for buildings;
 FIG. 5 is a rear elevational view of a stud for buildings;
 FIG. 6 is a top plan view of a stud for buildings; and
 FIG. 7 is a bottom plan view of a stud for buildings; and,
 FIG. 8 is a cross section view of FIG. 4 taken along line 8-8.
 FIGS. 1-5 contain symbolic elongated dashed break lines.
 The portion between the elongated break lines forms no part
 of the claimed invention.

1 Claim, 2 Drawing Sheets(56)
